Company, Swissvale, Pa., a corporation of
PennsylvaniaApplication April 9, 1935, Serial No. 15,378
In Great Britain April 27, 1934

6 Claims. (Cl. 246—3)

This invention relates to the electric control and indication of point operating mechanisms for railways and the like of the kind in which the point machine or other mechanism for effecting the setting of the points is arranged to be operated by direct current supplied from the point of control through a pair of line wires which may also be utilized for the purpose of indicating the setting of the points by means of an alternating current transmitted from the points to the point of control.

The invention has for its object to provide improved arrangements for control and indication of this character and according to the principal feature of the invention the operation of the point machine or its equivalent is arranged to be under the sole control of a polarized single arm control relay located at the points, this relay being normally deenergized so long as the position of the points fully corresponds to that of the point lever or its equivalent at the point of control, any want of correspondence in this respect due either to the reversal of the point lever or its equivalent to set the points from one position to the other or to an unintentional displacement of the points from either position being arranged to cause the control relay to be energized so as to effect the supply of operating current to the point machine.

The apparatus of our invention is an improvement over that disclosed in the copending application Serial No. 323,286, filed December 3, 1928, by Lester E. Spray for Multiple control apparatus.

The invention is illustrated by way of example in the accompanying drawing the single figure of which is a diagrammatic view of a point operating mechanism provided with control and indication arrangements embodying one form of the invention.

Referring now to the drawing it will be seen that the point of control G and the point operating mechanism P are arranged to be connected by a pair of control line conductors 1, 2 and an indication line conductor 3. At the point of control a point lever 4 is provided adapted when in its normal extreme position N as shown to close contacts 5, 6 and when in its reverse extreme position R to close contacts 7, 8, the lever 4 being also adapted to maintain a contact 9 closed during its movement from the N position to an intermediate position A and to maintain a contact 10 closed during its movement from the position R to an intermediate position E.

The point operating mechanism P which forms a part of the switch movement SM controlling the track switch S, comprises a point operating

motor M having an armature 11 and a field winding 12. A polarized single arm control relay O is provided at or adjacent to the motor M, one terminal of the energizing winding 13 of the relay O being directly connected by a wire 14 to the line conductor 2, the other terminal being connected by a wire 15 to the contact arm 16 of a circuit controller V operated by the movement of the points or of the point machine. The contact arm 16 is arranged to cooperate with two contact segments 17, 18 which overlap each other to a considerable extent so that the contact arm 16 is in engagement only with one segment or the other when the points are fully set into a corresponding normal or reverse position, while when the points are in an intermediate position the contact arm 16 is in engagement with both contact segments 17, 18. The segments 17, 18 are connected to the line conductor 1 through rectifiers 19, 20 respectively, the two rectifiers being oppositely arranged as shown so that when the point lever 4 is in its normal position N, for example, and the points are also in their corresponding full normal positions, the rectifier 19 connected to the contact segment 17 which is in engagement with the contact arm 16 of the circuit controller V will prevent the flow of current from the line conductors 1, 2 through the control relay winding 13. The control relay O will thus under these conditions be deenergized but in the event of the point lever 4 being moved to its reverse position R so as to reverse the polarity of the line conductors 1, 2 the rectifier 19 will permit the flow of current through the relay winding 13 which will thus be energized.

Furthermore, in the event of the points being displaced from their normal settings while the point lever 4 is in its normal position, the contact arm 16 of the circuit controller V will engage with both contact segments 17 and 18 and current will thus be supplied to the relay winding 13 through the other connected rectifier 20.

It will thus be seen that any want of correspondence between the position of the point lever 4 and the setting of the points will effect the energization of the control relay O by current of one polarity or the other according to whether the point lever 4 is in its normal or reverse position.

The movable contact 21 of the control relay O is directly connected to the line conductor 1 and is arranged to engage with one or the other of two fixed contacts 22, 23 which are connected through reverse and normal switches UN, UR operated by the circuit controller V to the ter-

minals of the field winding 12 of the point operating motor M. The terminals of the field winding 12 are connected through oppositely connected rectifiers 24, 25 to one terminal of the motor armature 11 the other terminal of which is connected to the line conductor 2.

The switches UR and UN comprise movable contact arms 26, 27 respectively operated by the circuit controller V and adapted to engage with contact segments 28, 29 connected to the contacts 22, 23 respectively of the relay O, the contact arm 26 being out of engagement with the corresponding segment 28 only when the points are in their full normal position while the contact arm 27 is out of engagement with the segment 29 only when the points are in their full reverse position.

The operation of the apparatus as so far described is as follows:

Assuming that the point lever 4 is in its normal position N and the points are in their full normal setting, the control relay O will be de-energized as above explained and if now the point lever is moved to its R position to reverse the setting of the points, a circuit will be completed from the positive terminal 30 of a source of supply of direct current through lever contact 7, line conductor 2, wire 14, relay winding 13, wire 15, contact arm 16 of circuit controller V, contact segment 17, rectifier 19, line conductor 1, and lever contact 8 to the negative terminal 31 of the source of current.

The control relay O will thus be energized and will move its contact arm 21 into engagement with fixed contact 23. A circuit will thereby be completed from terminal 30, through lever contact 7, line conductor 2, the armature 11 of the motor M, rectifier 24, field winding 12, contact arm 27 of switch UN, segment 29, contact 23, contact arm 21, line conductor 1 and lever contact 8 to the terminal 31.

The motor M will thus be started into operation to reverse the points and as soon as the point movement has been completed the motor circuit above described will be interrupted at the contact arm 27 of the switch UN. Immediately afterwards the circuit controller V effects the deenergization of the control relay O by the interruption of the circuit of the winding 13 at the contact arm 16 whereupon the relay contact arm 21 will return to its normal position out of engagement with either of the fixed contacts 22, 23 as shown in the drawing.

A similar cycle of operations will be performed if the point lever 4 is restored to its normal position N, the control relay being energized by current in the opposite direction, from the terminal 30, through lever contact 5, line conductor 1, rectifier 20, contact segment 18 of circuit controller V, contact arm 16, wire 15, relay winding 13, wire 14, line conductor 2 and lever contact 6 to terminal 31. The contact arm 21 is thereupon moved into engagement with fixed contact 22 and current is supplied to the motor M from terminal 30, through lever contact 5, line conductor 1, contact arm 21, contact 22, contact segment 28 of switch UR, contact arm 26, field winding 12, rectifier 25, armature 11, line conductor 2 and lever contact 6 to terminal 31. The motor M is thus rotated in a direction to effect the setting of the points to their normal position and when this has been completely effected, the relay O is deenergized as above described.

It will be observed that the field winding 12 of the motor M is permanently shunted by a

circuit including the two rectifiers 24, 25 connected to one terminal of the motor armature 11, this circuit constituting a discharge path for the reactive current generated when the supply of current to the motor M is interrupted. The field excitation thus tends to be maintained or prolonged and assists the action of a "snubbing" circuit which is preferably provided for the motor armature 11 for each direction of rotation, this circuit including the armature 11, the corresponding rectifier 24 or 25, the field winding 12, a contact 32 or 33 closed by the normal or reverse switch UN or UR when in its extreme position and a directional switch 34 or 35 which is closed so long as the armature 11 is rotating in the corresponding direction. The purpose of the directional switch is to prevent short-circuiting of the armature 11 through the snubbing circuit which includes the rectifier 25 or 24 and the associated contact 27-33 or 26-32, respectively, at such time as it is desired to apply power to the motor. This snubbing circuit, if uninterrupted when armature 11 comes to a standstill, would interfere with the proper operation of motor M during a subsequent reversal of the switch S.

It will be noted that the control relay O is not during any part of the operation of the points required to break a current carrying circuit so that the control relay contacts 21, 22, 23 may be of very light construction.

Referring now to the arrangements for indicating the setting of the points at the point of control G, the third line conductor 3 is connected at the point of control through one winding 36 of a point indication relay K of the two-element alternating current type to one or other of the control line conductors 1, 2 through the lever contacts 9 or 10 according to whether the point lever 4 is in its normal or reverse position.

At the points an indication controller Y is provided which is diagrammatically shown as comprising cam members 37, 38 operated by the point tongues and arranged to operate movable contact arms 39, 40, 41, 42 which are adapted to cooperate with fixed contacts 43, 44, 45, 46 connected together by a wire 47. The contact arms above referred to are also adapted to cooperate with fixed contacts 48, 49 connected to one terminal of a source of alternating current indicated as the secondary winding 50 of a transformer T and with fixed contacts 51, 52 connected to the other terminal of the winding 50. The purpose served by contacts 43, 44, 45, and 46 is to maintain an effective short-circuit across the indication wires for insuring the deenergization of the indication relay K at all times except when one or the other of cams 37, 38 occupies its proper indicating position.

The line conductor 3 is connected to the contact arms 40 and 42, the line conductor 1 being connected through a condenser 53 to the contact arm 39 while the line conductor 2 is connected through a condenser 54 to the contact arm 41.

So long as the points are fully set in their normal position the parts of the controller Y occupy the position shown so that a circuit is completed from one terminal of the transformer winding 50 through contact 48, contact arm 39, condenser 53, line conductor 1, lever contact 9, relay winding 36, line conductor 3, contact arm 40 and contact 51 to the other terminal of the winding 50.

When on the other hand the points are fully reversed the line conductor 3 is connected to the

other terminal of the transformer winding 50 to that above described the circuit of the relay winding 36 being completed through the line conductor 2 and condenser 54 so that the indication given by the relay K is correspondingly reversed.

5 It will be observed that the condensers 53, 54 isolate the source of alternating current utilized for indication from the direct currents in the control line conductors 1 and 2, while on the other hand the alternating current is prevented 10 from flowing through the battery or other source of control current.

10 The condensers 53, 54 may if desired be so designed as to produce series resonance in the 15 indication circuits in conjunction with the inductances of these circuits so as to increase the indication currents flowing and in the event of a condenser becoming short-circuited a marked decrease in the voltage at the indication relay K will result thus causing the release of the relay. 20 It will be understood that the indication relay K or its equivalent may be arranged to give a continuous indication of the setting of the points or to control the movement of the point lever 4 to 25 its full normal or release position in the well known manner.

If desired, the arrangements for controlling the point operating mechanism above described may evidently be employed in connection with other arrangements for effecting the indication 30 of their setting involving separate line wires for this purpose.

The invention may be applied to control systems in which two point operating mechanisms are controlled from a single point lever or its equivalent, only a single pair of control line conductors being necessary since the control relay O completely isolates each point machine at the 35 end of the point movement.

The invention is evidently not limited to the 40 particular arrangements and connections above described and illustrated by way of example which may be varied in many respects without exceeding the scope of the invention.

Having now particularly described and ascertained the nature of our said invention and in what manner the same is to be performed we declare that what we claim is:

1. In combination with a track switch, a normally deenergized polarized control relay at the 45 track switch location and having a normally open contact which assumes a normal or a reverse position according as said control relay is energized in the normal or the reverse direction respectively, means effective when said contact occupies its normal or reverse position for selectively operating said track switch to its normal or reverse position respectively, means including a lever having a normal and a reverse position for selectively energizing said control relay in the 50 normal or the reverse direction in accordance with the position occupied by said lever, and means automatically effective whenever said track switch and said lever are out of correspondence for energizing said control relay to thereby operate said track switch to a position in agreement with the position of said lever.

2. In combination with a track switch, a normally deenergized polarized control relay having 55 a contact which assumes a normal or a reverse position according as said control relay is energized in the normal or the reverse direction respectively, means effective when said contact occupies its normal or reverse position for selectively operating said track switch to its normal or

reverse position respectively, a lever having a normal and a reverse position for selectively closing a normal or a reverse energizing circuit for said control relay in accordance with the position occupied by said lever, and a circuit controller governed by said switch and having a first contact included in said normal energizing circuit which first contact remains closed at all times except when the switch occupies its extreme normal position as well as a second contact included 10 in said reverse energizing circuit which second contact remains closed at all times except when the switch occupies its extreme reverse position, whereby a displacement of the switch from either extreme position causes said control relay to become energized for restoring said switch to a position in agreement with the position occupied by said lever.

3. In combination with a track switch, a normally deenergized polarized control relay having 20 a contact which assumes a normal or a reverse position according as said control relay is energized in the normal or the reverse direction respectively, means effective when said contact occupies its normal or reverse position for selectively operating said track switch to its normal or reverse position respectively, a lever having a normal and a reverse position for selectively closing a normal or a reverse energizing circuit for 25 said control relay in accordance with the position occupied by said lever, a rectifier poled in the normal direction included in said normal energizing circuit, a rectifier poled in the reverse direction included in said reverse energizing circuit, and a circuit controller governed by said switch 30 and having a first contact included in said normal energizing circuit which first contact remains closed at all times except when the switch occupies its extreme normal position as well as a second contact included in said reverse energizing 35 circuit which second contact remains closed at all times except when the switch occupies its extreme reverse position.

4. In combination with a track switch, an electric motor for operating said switch, a normally 45 deenergized polarized control relay having a contact which assumes a normal or a reverse position according as said control relay is energized in the normal or the reverse direction respectively, a lever having a normal and a reverse position for 50 selectively closing a normal or a reverse energizing circuit for said control relay in accordance with the position occupied by said lever, means comprising a circuit including a first rectifier and also a contact of said lever and effective when 55 said relay contact occupies its normal position for causing current to flow through both the field and armature of said motor in the normal direction whereby said switch is operated to its normal position, and means including a second rectifier 60 and effective when said relay contact occupies its reverse position for causing current to flow through said motor field in the normal direction and through said motor armature in the reverse direction whereby said switch is operated to its 65 reverse position.

5. In combination with a track switch, an electric motor for operating said switch, a normally deenergized polarized control relay having a contact which assumes a normal or a reverse position according as said control relay is energized 70 in the normal or the reverse direction respectively, a lever having a normal and a reverse position for selectively closing a normal or a reverse energizing circuit for said control relay in accord- 75

5
10
15

25
ance with the position occupied by said lever, means including a first rectifier and effective when said contact occupies its normal position for causing current to flow through both the field and armature of said motor in the normal direction whereby said switch is operated to its normal position, means including a second rectifier and effective when said contact occupies its reverse position for causing current to flow through said motor field in the normal direction and through said motor armature in the reverse direction whereby said switch is operated to its reverse position, and a circuit controller governed by said switch and having a first contact included in the normal energizing circuit for said control relay which first contact remains closed at all times except when the switch occupies its extreme normal position as well as a second contact included in said reverse energizing circuit which second contact remains closed at all times except when said switch occupies its extreme reverse position.

6. In combination with a track switch, an electric motor for operating said switch to its normal or reverse position according as said motor is

energized in the normal or the reverse direction respectively, means for at times closing a normal energizing circuit for said motor and for at other times closing a reverse energizing circuit for said motor, a circuit controller governed by said switch and having a first contact included in said normal energizing circuit which first contact remains closed at all times except when the switch occupies its extreme normal position as well as a second contact included in said reverse energizing circuit which second contact remains closed at all times except when the switch occupies its extreme reverse position, a first and a second snubbing contact closed by said controller when the switch occupies its extreme normal and its extreme reverse position respectively, and a directional switch governed by said motor and effective provided said motor is rotating in the normal direction for closing a first snubbing circuit through said first snubbing contact and effective provided said motor is rotating in the reverse direction for closing a second snubbing circuit through said second snubbing contact.

RODERICK MARCUS MACGREGOR.
